APPARATUS FOR COLONIC THERAPY

Alice Touchberry, Palm Beach, Fla.

Application September 30, 1947, Serial No. 777,084

9 Claims. (Cl. 128—33)

1

This invention relates to apparatus for colonic therapy, and more particularly to tables and co-operating appurtenances for intestinal and like treatments such as involve the introduction of liquids for cleansing, irrigation, medication or other purposes. While deep and vigorous injection of liquid has often been thought to constitute a chief criterion of therapeutic methods of this type, the present invention is designed to provide novel means for effectuating colonic treatments in accordance with special principles that have now been found of peculiar importance. For instance, the comfort of the patient, the facility with which the operator may handle the equipment and observe results, and especially the position of the patient's body with respect to gravity or physiological forces acting on the liquids and wastes, are factors of prime significance, in an inter-related manner. A more comfortably supported patient is in a more relaxed condition, allowing better penetration of the injected liquid with less pressure, and permitting fuller realization of any desired muscular or other physiological reaction of the organs under treatment. At the same time, by positioning the patient so that full advantage may be taken of gravity to assist the inward or other flow of liquid, very low pressures may be employed and deep insertion of instruments avoided; in consequence the patient's comfort is again enhanced, with further resulting benefit in the effectiveness of the treatment, as explained above. Improvement in these respects also makes administration of the process easier for the operator, and to the extent that the several parts of the apparatus can be more readily controlled or adjusted, and the character of results more directly detected, the attainment of a desired therapeutic benefit without discomfort to the patient passes from the realm of guesswork to that of scientific certainty.

A chief object of the invention, therefore, is to provide improved apparatus having the characteristics described above for promoting the efficacy and convenience of such treatments, a further object being to provide equipment of the stated kind, which affords a maximum of comfort to the patient and which permits a definite avoidance of pain and physiological harm.

Another primary object is to provide a novel table for treatments of the character described, including means for supporting the various parts of the patient's body in an eminently comfortable manner which at the same time promotes the effects of the treatment and facilitates its ad-

2

ministration. Other objects are: to provide apparatus of the stated nature, including improved supporting arrangements of an adjustable character and having proportions and dimensions found peculiarly effective for the desired results; to provide such apparatus having novel means for receiving and removing waste, i. e. discharged material, the waste-receiving means cooperating structurally and functionally with the supporting and other elements of the table and also affording ready inspection of the discharged material; and to provide an arrangement of the stated instrumentalities, together with liquid supply means, which is adapted for convenient manipulation or adjustment by the operator.

A further and particularly important object of the invention is the provision of a colonic therapy table comprising improved waste-receiving and supporting structure (preferably having adjustable portions) wherein the supporting arrangement includes means to provide a massaging motion appropriate to the treatment that is being administered.

To these and other ends, including such as will become apparent from the following description or may otherwise be inherent in the improved apparatus, certain advantageous embodiments of the invention are shown in the drawings and described hereinbelow, by way of example to illustrate the several features, combinations and principles of improvement.

Referring to the drawings:

Fig. 1 is a side elevation of one form of the improved table for colonic therapy, a portion of the side enclosure being broken away to reveal certain mechanical parts;

Fig. 2 is a plan view of the table of Fig. 1;

Fig. 3 is an end elevation of the table as viewed from the left-hand side of Fig. 1, a portion of the table enclosure being broken away;

Fig. 4 is a fragmentary perspective view showing a portion of the table embodying a combined supporting and massaging arrangement in accordance with the invention;

Fig. 5 is an enlarged, fragmentary elevation of the structure of Fig. 4, partly in central, vertical section;

Fig. 6 is a section on line 6—6 of Fig. 5;

Fig. 7 is a section on line 7—7 of Fig. 5, but showing the movable structure rocked away from a central position; and

Fig. 8 is a fragmentary perspective view of certain parts shown in Fig. 4, with alternative connections for a different type of motion.

The illustrated embodiment of the apparatus,

as shown for example in Figs. 1 to 3, comprises a table generally designated 10, which may be built as a cabinet, if desired, and which has a top 11 including a central supporting structure 12. A plane support element 14 is hinged for vertical adjustment on one side of the central section 12, and another support element 15 is similarly hinged to swing vertically on the other side of the portion 12. The table also has a further, stationary supporting surface 16 beyond the rising part 15, the complete arrangement being designed to receive a patient in reclining position, with his back and head resting on the portion 14, the upper part of his legs on the support 15, and his knees disposed over or beyond the outer edge of the latter so that his feet rest on the surface 16, e. g. against a weighted foot rest 18. It will be understood that the table or parts of it may be manufactured of wood, metal or other suitable material; for instance the structure shown is made chiefly of wood, and includes an appropriate bracing and supporting framework 19, the sides being conveniently closed by panels 20 with suitable doors for access to the working parts hereinbelow described.

The sections 12, 14 and 15 for supporting the patient are preferably cushioned. For example, the central member 12 and the leg rest 15 may carry a pad 21 of sponge rubber or the like, say one inch thick, removably seated so that it can be taken off for cleaning the apparatus. A removable pad 22 is also provided for the back support 14, and is advantageously of an upholstered or mattress-like character for a relatively deep cushioning effect. Supplemental pads may likewise be employed, such as a pillow 24 for the patient's head and a small, highly elastic cushion 25 which can be placed, for instance, over the junction of the pads 21 and 22 to support the small of the patient's back.

A waste-receiving vessel comprising a bowl 28 opens through the top of the table at a central region, e. g. partly through the support portion 12 and partly through the leg rest 15; both of the latter parts have curved openings to conform with the corresponding regions of the mouth of the bowl, as shown in Figs. 1 and 2, and the pad 21 has a similar aperture. A curved guard or shield 30 is carried by the adjustable support member 15, depending from the opening in the latter, i. e. from all parts of the edge of the opening, and the shield 30 is shaped to telescope within the bowl 28 so that when the support 15 is raised, e. g. to any upper position such as indicated by dot-and-dash lines, the shield forms an extension of the wall of the waste-receiving vessel, thus insuring that material eliminated or discharged by the patient, or any other released flow of liquid, will be caught by the bowl. Hence the patient may be supported in a particularly advantageous manner, both for comfort and for therapeutic purposes of the treatment, and at the same time the mechanical removal of discharged material or surplus liquid is always efficiently and completely achieved. The outlet from the bowl 28 extends through a trap 31, which may comprise a curved pipe section of considerable length, made of glass or other transparent substance to permit visual examination of the discharged materials, as with the aid of an electric lamp 32 behind the trap. The outlet from the trap extends to a suitable drain conduit, either directly or through a further trap 33 having a plug 34 which is re-

movable so that samples of the effluent can be withdrawn for analysis or other examination.

Hot, warm or cold water or other liquids or solutions used in the treatments may be derived from any suitable source; by way of example, the illustrated apparatus includes an upright cabinet section 35 mounted at the foot of the table, and containing tanks (not shown) from which liquids may be dispensed as needed, it being understood that the cabinet 35 may also enclose suitable heating or other temperature-controlling means (not shown) for the liquids. The amount of contents and the temperature condition of the tanks may be indicated by suitable gauges 36, and the supply of solutions, water or other liquids to the tanks and especially to the table from the tanks or from the supply mains 37 (both for treatment purposes and for flushing the bowl 28), can be controlled by suitable valves 38—it being desirable to regulate carefully the pressure and rate of flow of the liquid injected for treatment.

Correspondingly necessary pipes connect the cabinet section 35 with the table proper. For example, a pipe 40 extends to a suitable fitting 41 at an upper part of the bowl so that a spray or stream of water may be projected into and around the bowl to flush it; if desired the fitting may be mounted on the guard 30, the pipe 40 then including a flexible portion to permit the necessary changes of position. To feed the various solutions or other liquids for the colonic treatment, a pipe 42 also extends from the supply and regulator cabinet, and continues through a flexible tube 43 to a check valve 44 which is mounted at a central, outer locality of the support 15 and which has an outlet nipple 45. A flexible connecting tube 46 is fitted over the nipple and terminates in a suitable, thin, rectal injection tube 48 designed to be inserted in the rectum of the patient, but preferably only to a distance of several inches or less. Thus the desired liquid can be injected continuously into the colon of the patient, outflow from the latter taking place either simultaneously around the tube or upon its removal, depending on the condition or stage of treatment. The check valve 44 serves an important sanitary function in preventing any back flow of liquid into the conduit 43-42, i. e. into a locality that cannot be easily cleaned and sterilized.

Means are provided for raising and lowering the otherwise freely swinging table sections 14 and 15, and while other powered instrumentalities may be used, such as electrically actuated lifts, the apparatus shown embodies, by way of example, a pair of hydraulic jacks 50, 51, respectively controlled for lifting operation by pedals 52, 53, and assisted in their return or downward movement (upon interruption of the supplied hydraulic pressure, by means not shown) by sets of coil springs 54, 55. The plunger 57 of the jack 51 is pivotally connected (with necessary lateral freedom of motion) to a crank arm 58 on a shaft 60 which carries a pair of arms 61 linked by push rods 62 to the underside of the support member 15. Thus when the jack plunger 57 rises, the arms are swung clockwise (in Fig. 1) and the member 15 tilts upward, coming to rest whenever the attendant releases his pressure on the pedal 53. Likewise the plunger 64 of the jack 50 is linked by the U-shaped actuating rod 66 to the underside of the support section 14, for similarly controlled, vertical displacement of the latter about its horizontal axis of swing.

In accordance with a further feature of the invention, means (not shown in Figs. 1 to 3) are preferably provided for automatically applying a massaging motion to the patient, specifically means structurally and functionally combined with the central supporting structure 12. To that end, at least a substantial part of the latter is movably mounted, and driving means are included for reciprocating the movable section, e. g. instrumentalities selectively adapted to rock it crosswise of the table or simply to vibrate it. While any of a variety of mechanical arrangements may be employed to fulfill this part of the invention, one suitable construction is shown, simply by way of example, in Figs. 4 to 8 inclusive, wherein all parts not shown may be identical with corresponding elements of Figs. 1-3. Referring first to Figs. 4 to 7, substantially all of the central table section 12, except for a strip 70 sufficient to mount the hinges or pivots for the leg support 15 and to surround the forward portion 71 of the bowl 28, is constituted by a platform 72 having an opening or recess 73 which clears the bowl 28 sufficiently (i. e. at the sides) to permit the desired motion of the platform. The platform 72 is secured on a multiplicity of strong coil springs 75 which are mounted on a carriage 76. The carriage is fitted with four wheels 78, adapted to roll on two pairs of curved track sections or rails 79 so that it may be rocked, within a limited distance, about an axis lying well above the top of the table.

A pair of arms 80 are secured to the ends of the platform 72 and extend down from the latter through guide and retainer plates 81 on the ends of the carriage. The lower ends of the arms are fastened to a cross bar 82. To permit rocking motion of the assembly (see Fig. 7) the table frame is suitably notched or recessed at the vicinity of the arms 80, the structural continuity of the table being provided by reinforcing beams 84 (Figs. 5, 6 and 7) extending past either side of a housing 85 around the bowl 28. Removably secured to the bar 82 on three pins 87, a bifurcated plate 88 depends from the bar, providing a long vertical cam slot 89 to be traversed by a roller 90. The roller 90 is rotatably carried on a pin 91 which may be removably seated in any one of a series of holes 92 in the face of a disk 93 mounted on a shaft 94. The shaft is journaled in a suitable bearing 95 and is driven through gearing 96 by a variable-speed motor and transmission unit 98 of suitable character.

Thus as the motor drives the disk 93, the eccentric roller 90 in the slot 89 moves the plate 88 from side to side, and the carriage 76 and platform 72 are similarly reciprocated with a rocking motion, by reason of the curved shape of the rails 79 (cf. Figs. 6 and 7). The length of stroke may be adjusted, to suit the requirements of this type of massaging motion to the particular purposes of a given treatment, by changing the pin 91 to a hole of different eccentricity relative to the shaft 94, and the speed or frequency of reciprocation may likewise be varied by adjusting the speed of the motor drive 98.

If it is desired to vibrate the central support of the table, i. e. the platform 72, in a vertical direction alone, the plate 88 is replaced by a link 100, pivoted on one of the pins 87 and on the roller 90, as shown in Fig. 8. To prevent transverse motion of the carriage, retaining bars 102 on either side of the table are slid through guide plates 103, 104 so that they obstruct any lateral motion of the arms 80; and each bar 102 may

have an upper hook-like projection 105 which is adapted, when the bar is moved to restraining position, to engage the upper surface of a pin 106 on the carriage 76, so that the latter cannot move vertically. Thus assuming that the link 100, of suitable length, is initially fitted to the pin 87 and roller 90 when the latter is associated with a selected hole 92 (usually the innermost one, of least eccentricity) and conveniently when the disk 93 is disposed with such hole in its lowermost position, operation of the driving motor will reciprocate the link in the manner of a connecting rod. The platform 72 will be correspondingly vibrated, against the springs 75 and in a vertical direction; the arms 80 are adapted to slide only in such direction under the retaining plates 81 and retaining bars 102, and the carriage 76 is positively held against any displacement. The arrangement shown in Fig. 8 thus provides an alternative type of massage, e. g. a simple vibration, which is of value in at least some kinds of treatment for which the table may be used.

The pad on the sections 12 and 15 may be made in two corresponding portions in the structure of Figs. 4 to 8, so that the pad portion 107 on the platform 72 is separate and free to move with the latter; if desired it may conform much more closely to the bowl opening than does the platform, and may have a skirt 108 of flexible, waterproof material depending in the opening. That is to say, the pad portion 107 is separate from the remaining pad portion 107a (Fig. 4) which covers both the section 15 and the straight part of the section 70, the pad portions together corresponding to the pad 21 of Figs. 1 and 3. The pad 107 has an opening which conforms with that of the bowl 28, the pad 107 conveniently overlapping the upper edge surface 70 of the bowl housing 85; such upper edge surface, as described above, may be considered as that part of the stationary portion 70 of the center section (generally designated 12) which goes around the bowl. As shown in Fig. 7, when the platform 72 is rocked one way, the under side of the pad 107 at one side of the bowl may be engaged by a corner of the edge 70, compressing the pad at this locality, while on the other side of the bowl the pad may be stretched between the skirt 108 and a locality where the pad frictionally grips the platform surface, the compression and stretching of the pad 107 being reversed when the platform 72 is rocked the other way.

Referring again to Figs. 1-3, further and particularly important features of the invention reside in certain structural and dimensional relationships among the supporting sections of the table. In the first place, it is extremely advantageous for the section 14 to be so located relative to the supports 12 and 15 that the upper part of the patient's body, i. e. the upper part of his back, can rest at a level lower than his hips (or any other part supported by the sections 12 and 15), even when the support 14 is tilted substantially upward. Under such circumstances, with the illustrated table, the patient is comfortably supported and may even believe that his back is at a higher level, but the actually lower disposition of his back is of great importance to the colonic treatment, especially in effectuating (with the aid of gravity) a deep but gentle penetration of liquid such as cannot be conveniently or comfortably obtained by means of high pressure injections through deeply inserted instruments. In defining the levels of the several table sections herein, it will be understood that each

must be considered as including its padding, cushion or the like—the effective supporting surface being that of the padding or cushion, lowered somewhat by the natural depression of the patient's weight.

As stated, the hinging of the member 14 at a level lower by several inches (say, 3 or 4 inches) than the member 12, and the selection of a suitable thickness for the cushion 22, permit the desired difference in levels of support (especially considering the cushion 22 more or less depressed as shown at 110 in Fig. 1) when the member 14 is horizontal or is tilted at any angle up to about 15° to the horizontal. At greater angles, the difference in levels is reversed, such condition being desirable (i. e. for ejection of fluid) at some stages of certain treatments. In some cases, the construction may be such as to provide for even greater tilt without raising the patient's shoulders above his hips, but generally, provision should be made to reach such condition at least at an angle of about 30° (or preferably less as in the apparatus shown).

For optimum support of the patient, the dimensions, lengthwise of the table, of the sections 12 and 15 are of great importance, and may be considered to be of a critical nature if the table is to be used with equal satisfaction for treating patients of widely different sizes, proportions, ages and weights. More specifically, in a greatly preferred design of table, adaptable to extremely wide variation among patients, the dimension 112 of the central structure should be about six to seven inches, and the dimension 115 about 18 inches. In one such table, the bowl opening is about 14 inches long, overlapping the portion 12 (so to speak) by about 4 inches. At least for good results with considerable difference among patients, the central dimension 112 may be 4 to 8 inches, and the dimension 115 may be 12 to 18 inches. Substantial departures from these dimensions are apt to cause discomfort to some patients or impair their full realization of the benefits of treatment. Conveniently the foot portion 16 of the table has a level lower than the top of the cushion 21 by two or three inches.

It will now be seen that the described apparatus is of definite advantage in promoting the patient's comfort and in effectuating the desired therapeutic treatment. The patient rests in a comfortable reclining position at all times, yet the position is one which is peculiarly suited to the treatment; he need not sit up, turn over or move in any other way at any stage. He can, however, be changed in position by the operator's control, while the several injection and waste-collecting means always remain in optimum location for their intended function. Likewise, without even moving the patient at all, massage of various kinds can be automatically administered, in a dorsal region, which is to be preferred for such purpose. The entire apparatus is easy to use and control, so that work of the operator is tremendously facilitated; and cleaning and sterilization of various exposed parts is readily achieved at desired times.

This application is a continuation in part of my copending application Serial No. 746,357, filed May 6, 1947, for Operating table. The invention of a colonic therapy apparatus having a transparent trap structure for observation of discharge material, which is disclosed herein, is being claimed in my aforesaid co-pending application, Serial No. 746,357, filed May 6, 1947.

It is to be understood that the invention is not

limited to the specific structures herein disclosed, but may be embodied in other forms without departure from its spirit as defined by the following claims.

5 I claim:

1. In apparatus for colonic therapy, in combination, a central supporting structure, a support for the upper part of a patient hinged adjacent one side of the central structure for vertical adjustment, a support for the upper part of the patient's legs having a normally horizontal position and hinged adjacent the other side of the central structure to swing upward for vertical adjustment to elevate the said upper part of the patient's legs above the central supporting structure, and a waste receiving vessel opening partly through said central structure and partly through said leg support.

2. In apparatus for colonic therapy, in combination, a table for supporting a patient in reclining position and a waste receiving vessel opening through said table at a central region thereof, said table including portions adapted to support respectively the upper part of the patient and the upper part of the patient's legs, said portions being mounted to swing about horizontal axes spaced respectively from opposite ends of the table for adjustment of their positions of support, said table including a central supporting structure separating the said swinging portions at the center region of the table, said central structure extending between said portions, said portion which is adapted to support the upper part of the patient's legs being pivoted adjacent the said central structure and being adapted to swing upwardly to elevate said part of the patient's legs to positions above the said central structure, and said vessel opening partly through said central structure and partly through said leg-supporting portion.

3. In apparatus for colonic therapy, in combination, a table for supporting a patient in reclining position and a waste receiving vessel opening through said table at a central region thereof, said table comprising a central supporting structure and portions hinged for vertical adjustment upward from a horizontal position on opposite sides of said supporting structure to receive respectively the upper part of the patient and the upper part of the patient's legs, and said central structure comprising a movable element adapted to be disposed beneath the patient and constituting part of the support for the patient, said movable element having means for reciprocating said movable element to agitate the supported portion of the patient.

4. In apparatus for colonic therapy, in combination, a table for supporting a patient in reclining position and a waste receiving vessel opening through said table at a central region thereof, said table comprising a central supporting structure extending about four to eight inches lengthwise of the table, a support for the upper part of the patient disposed on one side of said central structure and vertically adjustable, and a support for the upper part of the patient's legs disposed on the other side of the central structure and hinged on a horizontal axis adjacent said structure to swing upward for vertical adjustment to positions above said central structure, said leg support extending about twelve to eighteen inches lengthwise of the table, and said vessel opening partly through said central structure and partly through said leg support.

5. In table apparatus for colonic therapy, in

combination, a central supporting structure extending about four to eight inches lengthwise of the table, a support for the upper part of a patient comprising a substantially plane, cushioned member hinged adjacent one side of the central structure for vertical adjustment, a support for the upper part of the patient's legs hinged adjacent the other side of the central structure to swing upward for vertical adjustment to positions above said central structure, said leg support extending about twelve to eighteen inches lengthwise of the table, and a waste receiving vessel opening partly through said central structure and partly through said leg support, said cushioned, hinged member being disposed to have a horizontal position below the level of the central supporting structure and being hinged on an axis below the level of said central structure so that throughout a small range of angles of tilt up to about 15° above said horizontal position, said cushioned member is adapted to support the upper end of the patient's torso at a level below the lower end thereof when said lower end is disposed on said central structure.

6. In apparatus for colonic therapy, in combination, a table for supporting a patient in reclining position and a waste receiving vessel opening through said table at a central region thereof, said table comprising a central supporting structure and normally horizontal portions hinged to swing upward for vertical adjustment on opposite sides of said supporting structure to receive respectively the upper part of the patient and the upper part of the patient's legs, and said central structure comprising a movable element adapted to be disposed beneath the patient and constituting part of the support for the patient, said movable element having means for rocking the said movable element substantially transversely of the table, to agitate the supported portion of the patient, said vessel opening partly through said central structure and partly through the portion for receiving the upper part of the patient's legs.

7. In apparatus for colonic therapy, in combination, a central supporting structure, a support for the upper part of a patient hinged adjacent one side of the central structure for vertical adjustment, a support for the upper part of the patient's legs hinged adjacent the other side of the central structure to swing upward for vertical adjustment to positions above said central structure, and a waste receiving vessel opening partly through said central structure and partly through said leg support, said central structure comprising a movable element adapted to be disposed beneath the patient and constituting part of the support for the patient, said movable element having means for vibrating the said movable element to agitate the supported portion of the patient without substantially displacing said element in a direction transverse of the table.

8. In apparatus for colonic therapy, in combination, a central supporting structure, a support for the upper part of a patient hinged adjacent one side of the central structure for vertical adjustment, a support for the upper part of the patient's legs hinged adjacent the other side of the central structure to swing upward for vertical adjustment to positions above said central structure, and a waste receiving vessel opening partly through said central structure and partly through said leg support, said first mentioned hinged support being disposed to have a horizontal position below the level of the central supporting structure and being hinged on an axis below the level of said central structure so that throughout a small range of angles of tilt above said horizontal position but not beyond a predetermined angle which is less than 30° above the same, said first mentioned hinged support is adapted to hold the upper end of the patient's torso at a level below the lower end thereof when said lower end is disposed on said central structure.

9. In apparatus for colonic therapy, in combination, a central supporting structure, a support for the upper part of a patient disposed on one side of the central structure, a support for the upper part of the patient's legs hinged adjacent the other side of the central structure to swing upward for vertical adjustment to positions above said central structure, and a waste receiving vessel opening partly through said central structure and partly through said leg support, said leg support having a shield movable therewith and disposed in telescoping relation within the vessel to provide an extended wall for the vessel throughout a multiplicity of positions of said adjustment of said leg support, and said shield being open at the side thereof nearest the central structure so that the partial opening of the vessel through the central structure provides direct communication through the central structure into the vessel.
